Buckingham & Baird.

Milling Tool.

No 8,036.

Patented Apr. 15, 1851.

UNITED STATES PATENT OFFICE.

JOHN BUCKINGHAM AND JOSEPH H. BAIRD, OF WATERTOWN, CONNECTICUT,
ASSIGNORS TO THE SCOVILLE MANUFACTURING COMPANY.

IMPROVED MILLING-TOOL.

Specification forming part of Letters Patent No. 8,036, dated April 15, 1851.

To all whom it may concern:

Be it known that we, JOHN BUCKINGHAM and JOSEPH H. BAIRD, of Watertown, in the county of Litchfield and State of Connecticut, have invented a new and useful improvement in the apparatus by which a rotary die is employed to impress ornamental or other figures upon metal or other substances; and I do hereby declare that the following is a full and exact description of the said improvement.

The rotary die as heretofore employed has been capable of following such path only upon the surface to be impressed as it may follow without change in the position and direction of the axis about which it rotates.

The purpose of our improvement is to cause the rotary die to follow such paths upon the surface to be impressed as demand a vibratory motion in the axis of the rotary die.

Our improvement consists in placing the cheeks which hold the axle of the rotary die upon another axle, which is at right angles to the axis of rotation and not in the same plane, as is hereinafter more fully described, reference being had to the drawings annexed, and the letters of reference marked thereon, making part of this specification.

Drawing No. 1 represents in perspective the tool which is used. Drawing No. 2 represents the handle or holder into which it is to be fitted, and which forms a part of the tool. Drawing No. 3 is a sectional view of the tool and handle properly fitted to each other.

In Drawing No. 1, *a* represents an axle, to which is firmly attached a head-piece *b*, or both can be made in one piece.

c represents another piece of metal fastened to the head-piece *b* by means of the screw *e*, which works through a slot cut in *c*.

d is the rotary die, its axle *x* being at right angles with the axle *a*, and placed out of the line of the axle *a* to any desired extent by means of the slot in *c* and the screw *g*.

In order to apply this tool to the use for which it is designed, (as running ornamental knurls, beading, or borders or other figures on picture-frames, daguerreotype-mattings, metal boxes, cases, &c.,) we place it in the han-

dle or holder represented by Drawing No. 2, the end *t* of the axle *a* entering the eye or hole *j*, and another portion of it near the head-piece resting in the bearing *k* and being kept in place by the shoulder *l*, the axle *a*, with the parts attached to it, being free to move on its own axis. Then fasten the handle or holder into a rest of the kind ordinarily attached to a lathe for turning metals, and, having fastened the metal or other substance upon which the figure is to be impressed into the lathe, bring up the rest in such a manner that the axis of the rotary die will be parallel to the surface of the metal to be impressed and its periphery in contact therewith. The metal upon which the figure is to be impressed may then be made to revolve with a curvilinear motion by any known method, as in a circle on a common lathe, or in an ellipse or oval by means of a lathe fitted with eccentric machinery for that purpose, in either case the axle *a* being free to turn on its own axis and the center of the die *d* being out of the line of the axle *a*, it permits the die to follow the windings of a curve by a lateral vibratory or alternating motion. When the path which the die is to follow is not sufficiently determined by the motion of the surface on which the impression is to be made or by its form, a slight preliminary tracing will be sufficient to guide the die.

The rotary die for making impressions on metals and other substances is a well-known instrument, and we make no claim founded on that instrument in itself considered; but,

What we do claim, and desire to secure by Letters Patent, is—

The combination of such die with an axle on which the same may vibrate, which axle is at right angles with the axis of rotation and not in the same plane, substantially in the manner and for the purposes herein set forth.

JOHN BUCKINGHAM.
JOSEPH H. BAIRD.
